(57) CLAIM

I claim the ornamental design for a jewelry chest, as shown and described.

DESCRIPTION

FIG. 1 is a perspective view of the jewelry chest showing the new design;

FIG. 2 is a second perspective view thereof, with the drawers and door shown in an opened position;

FIG. 3 is a front elevational view thereof;

FIG. 4 is a right side elevational view thereof, the left side elevational view being a mirror image thereof;

FIG. 5 is a top plan view thereof; and,

FIG. 6 is a bottom plan view thereof.

The broken lines are for illustrative purposes only and form no part of the claimed design.
